W. Va.,

Application July 15, 1937, Serial No. 153,819

3 Claims. (CL 20—15)

This invention relates to improvements in wallboard construction and more particularly to wallboard units made from corrugated paper.

One of the objects of the present invention 5 is to provide an improved wallboard made of inexpensive material yet strong and durable in construction. A further object is to convert ordinary corrugated board as it is known into wallboard units by cutting, trimming and creasing standard size sheets into forms suitable for immediate application. A further object is to provide an improved wall insulating board 10 of the above general character which may be easily and quickly applied, and which when finished will be free from unsightly nail heads or exposed fastening means, seams or joints. A further object is to provide a wallboard unit 15 which may be associated with other units at any angle or in any position and when so positioned will not expose any markings either as to securing means or joints. A further object is to provide an improved fastening device for securing the units in place to the joists or other points 20 of the building. A further object is to provide an improved insulating unit which may be packed 25 and shipped in compact form without danger of injury to the outside surface or mutilation of exposed edges and particularly any overlap portion of the surface.

30 Other objects will be in part obvious from the annexed drawings and in part hereinafter indicated in connection therewith by the following analysis of this invention.

This invention accordingly consists in the features of construction, combination of parts, the unique relation of the members, and in the relative proportioning and disposition thereof, all as more completely outlined herein.

To enable others skilled in the art to fully comprehend the underlying features of the invention, 40 that they may embody the same by the several modifications in structure and relation contemplated by the invention, drawings depicting preferred forms have been annexed as part of this disclosure, and in such drawings like characters 45 of reference denote corresponding parts throughout the views, in which—

Figure 1 is a fragmentary perspective view 50 of one form of a complete unit shown in its folded position and having both overlap and underlap edges.

Figure 2 is a similar view of the same unit as it is being unfolded with a portion of adjacent board fitted thereto.

55 Figure 3 is a detail perspective view of an im-

proved fastening means holding a part in place.

Figure 4 is a detail perspective view showing manner of securing the adjacent edges of two boards, where no underlap is used.

Figure 5 is a detail view showing the decorative surface of two finished boards or one board 8 cut to fit a ceiling and wall corner.

Figure 6 is a detail perspective view showing the board applied to an inwardly extending 10 angle.

Figure 7 is a similar view showing the board as applied to an outwardly extending or projecting angle.

Figure 8 is a detail elevational view showing the manner in which two or more boards may 15 be joined with respect to studs.

Figure 9 is a detail sectional plan view of the parts shown in Figure 8.

Figure 10 is a detail perspective view showing the manner in which portions of the board may 20 be removed in order to provide additional overlaps as when and where necessary.

Figure 11 is a detail of a multiple-ply board.

Referring now to the drawings in detail and 25 more particularly to Figure 1 where the unit is shown in folded position, this unit is shown in its simplest form, that is it is made from a standard size single sheet of corrugated board, comprising a sheet 11 of corrugated paper which is 30 interposed between two sheets of relatively stiff 30 paper 12 and 13 but a plurality of these sheets 35 may be secured together as shown in Figure 11 if desired. The relative thickness of the several 40 sheets may also be varied as desired, but the board such as used in making ordinary packing 45 boxes of corrugated paper has been found satisfactory. These sheets are preferably cut to a width adapted to accommodate the distance between three studs of a building Figure 8. As is 50 well known to those familiar with buildings, these 55 studs are usually spaced either 16 or 24 inches apart; consequently the boards are usually made in units of 32 or 48 inches in width and of a suitable height. This height may vary say from 6 to 12 feet.

One edge of the board as shown in Figure 1 55 is preferably provided with an overlap portion 14 the purpose of which will be more fully hereinafter explained. This overlap usually consists of but a single thickness of paper. The back of 60 the board and along a line substantially parallel but slightly spaced to one side of the middle is 65 cut, the cut extending through the rear layer 12 and the corrugated sheet 11 as clearly shown in both Figures 1 and 2, whereupon the board 70

is folded over upon itself upon line 15, Figure 2, until the extreme outer edge of the overlap 14 is coincident with the extreme edge 16 of the other or underlap part.

- 5 It will thus be seen that when one part is folded over upon the other, as clearly shown in Figure 1, this overlap 14 is adjacent the lower portion of the unit whereby the folded unit may be packed with numerous other units in bundles 10 of 10 or 12 as desired and shipped without danger of mutilating the overlap. Further, the outside 15 or decorative finish is on the inside of the folded unit and consequently protected from dirt and damage.
- 15 Referring now to Figures 3 and 4, 17 represents an ordinary studding of a building and to which the unit is adapted to be secured. Only one upper corner of the unit is herein illustrated which includes the sheets 12 and 13 and interposed corrugated sheet 11 as referred to in connection with Figure 1. The overlap 14 is shown not only turned back to permit the fastening but is normally unsecured to the corrugated sheet 11 for a distance substantially equal to the width of the overlap, 20 i. e. about $\frac{3}{4}$ ". This is subsequently secured by adhesive either applied then or previously if of the water soluble kind.

The holding means illustrated in this view comprises a relatively small flat device 18 preferably of sheet metal having a somewhat pointed end 20 adapted to fit between the corrugations with its opposite end cut away or provided with a hole adapted to receive a nail as indicated at 21. It has been found that these holding devices 18 may be slid into one of the recesses of the corrugated board or over the corrugated board as shown whereupon the nail 21 is driven into the joists thus holding the board firmly against the studding 17. This holding device being of flat sheet 35 metal permits the next adjacent board as shown in Figure 9 to be tacked directly to the studding or if preferred the unit may be placed adjacent the studding and the single nail 21 holds both of the adjacent edges of the sheets in fixed position. It is particularly useful in securing the sheet to the intermediate joist as shown at the 40 right or left in Figures 8 and 9.

It may, however, be more desirable to omit this holding device and merely drive nails 21 through 50 the adjacent concealed edges of the two units as shown in Figure 4. The overlap 14 being free from the right hand board, the left hand board may be cut away at the edge as shown at the right of Figure 2 if desired, whereby the overlap 55 will lay flush in the cut away or underlap portion and cover the nail heads thus making a smooth overlap. It is, of course, desirable to use some simple form of adhesive for securing the overlap in position on the lower board which will not 60 smear or discolor the surface markings of the board as applied.

In Figure 5 there is shown an upper wall and ceiling corner illustrating how one board may be cut and folded or whereby any two boards may 65 be placed adjacent each other at any angle without showing the line of demarcation between the boards. The irregular mottled or unmatched design on the outer surface is especially important when used in such relation.

70 In Figure 6 there is illustrated the manner in which the unit may be folded to take care of a re-entrant angle in the wall to be covered, that is, the inwardly projecting angle at the corner of a room, for example. Wherever this angle occurs 75 with respect to the positioned unit it is only

necessary to take a sharp knife and cut through the rear wall 12 and the corrugated sheet 11 but not through the outer or decorative sheet 13. This permits the outer sheet surfaces to be moved relatively towards each other to any angle without breaking the finished surface 13 thereby to accommodate the unit to the reentrant angle without exposing any demarcation at the juncture or detracting from the insulating qualities of the board. 10

In Figure 7 the unit is shown as being applied to a projecting angle, that is the studding 17 projects outwardly into the room as where an L exists. Here the unit is applied in the same manner as in Figure 6 except that a rear surface 15 12 is grooved as by a V-shaped roller, for example, whereby the unit may be folded backwardly about the stud as clearly shown.

Referring to Figures 8 and 9, there is illustrated conventionally three adjacent studding 17 which 20 may be assumed to be each 16 inches apart and the units A and B are each of a width to accommodate the distance between the extreme right and the extreme left studding but for the purpose of illustration only the two adjacent 25 halves of the units A and B are shown. Thus we have the unit A provided with a relatively thick underlap edge indicated at 23 while the adjacent edge of the unit B is provided with the single thickness overlap 14. The securing may 30 be either by nails 21 or clips 18, as at the right, either of which would be covered by means of the overlap 14 as shown or joint 15—Figure 2. The adjacent or outside studding 17 merely permit the application of the units thereto and the securing thereof to prevent breaking. Here the clip 18 would be especially useful. In other words, the extreme right portion (not shown), of the unit B is secured and the illustrated half B bent back to permit the driving in of the nail or the application of the holding clip 18 as illustrated. This holding device as here applied is attached by means of the nail 21 whereupon the left hand side as illustrated of the unit B is swung inwardly to position against the middle studding 17 and its 40 securing means such as nails 21 are driven home after turning back the overlap 14. The next step is to apply the right hand portion of the unit A which may be done by driving its securing means 45 21 into the underlap portion and then its middle 50 to the left studding as shown whereupon the overlap 14 is adhesively secured in position, either by the application of adhesive or the moistening of a water soluble adhesive previously applied on the underlap or underside of the overlap. Thus 55 we have a substantially unitary appearing finished wall free from any exposed nail heads or fastening devices. 60

In Figure 10 there is illustrated the manner in which a portion of any unit may be further cut to provide an overlap at any place where desired. For instance, a board or unit having the inner sheet 12, the outer sheet 13 and the interposed corrugated sheet 11 as before is just cut along any line as for example line 24 extending through 65 the sheet 12 and the corrugated sheet 11 whereupon these two parts may be stripped clear of the sheet 13 by a simple downward pull.

If, however, the overlap is to take place on the upper edge of the unit as when mounting one 70 above the other or fitting to a wall-ceiling corner, Figure 5, then the cut is made along the line 25 in the manner previously described and the strip withdrawn along this line as clearly shown at the top of Figure 10. This feature is especially ad- 75

vantageous when it is desired to insulate both the walls and ceiling of a room without the unsightly appearance of unmatched design and exposed fasteners.

5 As thus seen, the present invention provides a simple and practical unit of wallboard construction which may be compactly folded for shipment with one or more other units as desired and with the assurance that the package will not suffer 10 unnecessary damage during transportation. The overlap which is highly desirable primarily for the purpose of concealing otherwise exposed fastening means is protected by the folding portion of the wallboard. The improved fastening device permits the use of a single means for securing the adjacent edges of two units with a single nail or it will permit the securing of the middle of the board adjacent the intermediate stud thereby to prevent a distortion of the board as 20 may otherwise occur. The improved surface design of the board permits the sheet to be applied in units or a unit cut and folded with the assurance that no noticeable line of demarcation between the units or parts is visible as has been an 25 objectionable feature in units of this character heretofore.

It is thus seen that the present invention contemplates an improved insulating wallboard accomplishing, among others, all of the objects and 30 advantages herein set forth.

Without further analysis the foregoing will so fully reveal the gist of the invention that others can by applying current knowledge readily adapt it for various applications without omitting certain features that from the standpoint of the prior art fairly constitute essential characteristics of the generic or specific aspects of this invention, and therefore such adaptations should and are intended to be comprehended within the 40 meaning and range of equivalency of the following claims.

I claim as my invention:

1. A wallboard unit comprising a sheet of corrugated paper between two relatively stiff sheets having along one edge an overlap formed by extending one of the stiff sheets beyond the corrugated paper, said overlap being unsecured to its corrugated sheet for a depth substantially equal to that of the extending overlap, said unit being folded back upon itself along a line slightly to one side of the longitudinal center line whereby when 10 folded the overlap will be protected against injury in transport by the portion of the board not provided with overlap. 5

2. A wallboard unit comprising a sheet of corrugated paper between two relatively stiff sheets 15 having along one edge an overlap formed by extending one of the stiff sheets beyond the corrugated paper, said unit being folded back upon itself along a line slightly to one side of the longitudinal center line whereby when folded the 20 overlap will be protected against injury in transport by the portion of the board not provided with overlap, said board having a decorative surface of irregular design whereby any two units may be placed edge to edge and eliminate the line 25 separating any two units.

3. A multi-layer wallboard unit, the outer layer of which is adapted to form an overlap along one edge of the unit, said unit having a cut through the rear layer and spaced from the edge of the 30 unit a distance substantially equal to the width of the overlap at the opposite edge whereby said rear layer may be stripped from the front layer to provide a free edge adapted to overlap the adjacent edge of another unit, and a single fastening means cooperating with the rear layer beneath the stripped overlap adapted to secure that unit and an adjacent unit to a studding or the like. 35

BURT B. REGER. 40
